UNITED STATES PATENT OFFICE.

NED WILLIAMS, OF EVANSVILLE, TEXAS.

MINE-CAR-CHECK LOCK.

1,330,669.

Specification of Letters Patent. Patented Feb. 10, 1920.

Application filed January 7, 1919. Serial No. 269,973.

To all whom it may concern:

Be it known that I, NED WILLIAMS, a citizen of the United States of America, residing at Evansville, in the county of Leon 5 and State of Texas, have invented new and useful Improvements in Mine-Car-Check Locks, of which the following is a specification.

The purpose of the invention is to provide 10 a device for use in conjunction with mine cars whereby the miner may place his check in a case carried on the front of the car and thereafter fill the car, the device being so constructed that the case may not be opened 15 until after the car has been emptied.

The invention is illustrated and described in a specific embodiment to which, however, it is not to be restricted. The right is reserved to make such changes or alterations 20 as the actual reduction to practice may suggest, in so far as such changes or alterations are compatible in spirit with the annexed claims.

The same numerals of reference designate 25 the same parts throughout the several figures of drawings, wherein:—

Figure 1 is a view in side elevation of a portion of the front end of a mine car showing the invention applied thereto.

Fig. 2 is a section on the line 2—2 of Fig. 1.

Fig. 3 is a view similar to Fig. 2 but showing the device in open position.

Fig. 4 is a perspective view of the movable plate comprising part of the device and in which there is formed a pocket for the miner's check.

Referring to the drawings, the invention is illustrated as applied to a mine car, the 40 front wall 1 of the body of which is shown. In this front wall there is formed a pocket 2 and in the back of the pocket a hole 3 which opens on the inside of the front wall.

Directly above the pocket 2 there is 45 mounted on the outside of the wall 1 a plate 4 preferably of rectangular shape, this plate being formed with flanges 5, extending laterally from its upper edge and two side edges.

Designed to coöperate with the plate 4 50 there is a second plate 6 which on the bottom edge is formed with a lug 7 designed to stand in the pocket 2 when the plate 6 is set against the plate 4 with the flanges 55 of the latter plate overlapping the edges of the former plate. On the inner face of the

plate 6 there is formed a pocket 8 of such shape and thickness as to receive the usual miner's tag and the plate 6 is slotted as indicated at 9, this slot 9 communicating with 60 the pocket 8, so that the tag may be inserted through this slot to drop in the pocket 8.

An ear 10 is formed on the plate 6 at the upper edge and at the top of the pocket 8, so as to assist in withdrawing the plate 6 65 from engagement between the flanges 5 of the plate 4, in opening the device in a manner hereinafter described.

Plate 6 is connected with an L-shaped bar the longer leg 11 of which hangs against 70 the front wall 1 of the car on the inside of the latter and the shorter leg 12 of which passes through the hole 3 and is attached in the lug 7. A plate 13 is mounted on the back of the wall 1 adjacent the hole 3 and acts 75 as a guard for the hole to prevent its enlargement by the L-shaped bar when the latter is shifted to effect the opening of the device.

The plate 6 stands normally against the 80 plate 4 surrounded on its edges by the flanges 5 of the latter, the longer leg 11 of the L-shaped bar then hanging against the inside face of the wall 1. In such a position of the several parts the miner fills 85 the car on which the device is attached when the longer leg of the L-shaped bar is hidden in the coal within the car and is precluded thereby from any movement. The miner then inserts his check through the 90 slot 9 and it falls into the pocket 8 from which it may not be removed except by shifting the plate 6 from between the flanges of the plate 4 which is prevented as long as the movement of the L-shaped bar 95 is precluded. The car is then transported to the dump for unloading and when empty the device may be opened by swinging the longer leg 11 of the L-shaped bar away from the inner face of the front wall 1. 100 This operation swings the plate 6 downwardly and away from the plate 4, the pocket 3 housing the lug 7 permitting such downward movement of the plate 6 as well as such downward movement of the lug 7 105 and leg 12 of the L-shaped bar. Of course, if the plates 4 and 6 should be so snugly engaged as to endanger the breaking of either the plate 6 or the lug 7 in separating the two plates by the raising of the leg 11 110 of the bar, the ear 10 may be employed to initially separate the plates 4 and 6.

With the plate 6 swung away from the plate 4, as shown in Fig. 3, access is had to the pocket 8 and the check contained therein.

5 An opening 14 is formed in the plate 6 at a point that will permit the reading through it of the number of the tag held in the pocket 8.

The invention having been described, 10 what is claimed as new and useful is:

1. In a check lock for mine cars, a plate attached to one wall of the car on the outside thereof, the said plate being formed with flanges, a second plate designed to lie 15 against the first said plate so that it is surrounded on the edges by the flanges of the latter, the second said plate being formed with a pocket designed to receive a check of the character described, and means connected with the second said plate and carried interior to the car, the said means holding the second said plate in position within the flanges of the first said plate and being 20 operable to swing the plates apart only 25 when the car is empty.

2. In a device of the kind described, the combination with a mine car, of a plate formed with a pocket therein, and means carried interior to the car and supporting 30 the plate which is exterior to the car, the said means being adapted to swing the plate away from the side of the car or into close contact with the latter and being operable only when the car is empty.

3. In a device of the kind described, the combination with a mine car, of a plate mounted on the exterior wall thereof and provided with flanges on a part of its perimeter, a second plate formed with a pocket 35 and engageable between the flanges of the first said plate, the second said plate being 40

formed with a lug, the wall of the car adjacent the first said plate being formed with a pocket in which the lug rests, and an L-shaped bar having one leg connected with the lug and the other leg disposed within the car so that when the said latter leg hangs against the inside wall of the car the two plates may be held together, the swinging of the said leg away from the said inside 50 wall of the car separating the two plates for the removal when the car is empty of a check inclosed within the pocket.

4. In a device of the kind described, the combination with a mine car, of a plate 55 mounted on the exterior wall thereof and provided with flanges on a part of its periphery, a second plate formed with a pocket and engageable between the flanges of the first said plate, the second said plate having 60 a lug, the wall of the car being formed with a pocket in which the lug rests, and an L-shaped bar having one leg connected with the lug and passing through the wall of the car and the other leg depending within the 65 car against the inside wall thereof whereby the two plates are held together to inclose the pocket of the first said plate when the car is full, the second said plate being formed with an ear on that edge opposite 70 the lug and further formed with a slot to permit the insertion therethrough of a tag to be carried in the pocket, that leg of the L-shaped member hanging within the car being adapted for swinging movement away 75 from the side wall thereof to separate the two plates to expose the pocket in the second said plate, the ear on said second said plate providing means for the initial separation of the plates

80 In testimony whereof I affix my signature.
NED WILLIAMS.
